ROLLING-WINDOW-SCREEN CONSTRUCTION

Application filed August 13, 1928. Serial No. 299,141.

This invention relates to window screens, and particularly to window screens adapted to assume a rolled form when not in use.

An object of the invention is to provide an improved means for accurately guiding a window screen as it is being rolled upon or withdrawn from a roller.

Another object is to engage the lateral edges of a roller type window screen with runways, and to adapt the latter for a resilient frictional engagement with said edges to hold the screen in selective positions against the pull of the roller spring.

A further object is to provide for regulation of the friction imposed by such runways upon the lateral margins of the screen, in a simple and improved manner.

Still another object is to maintain said screen reasonably taut by its engagement in said runways, while permitting its withdrawal from said runways responsive to an abnormal stress or shock.

A still further object is to maintain a substantially transverse relation between the free end of a roller type screen and runways in which said screen is slidably, by the use of improved guide members carried by said free end, adjacent to said lateral margins.

It is also an object of the invention to resiliently embrace the lateral margins of a sliding screen in suitable runways and to mount upon the free end portion of said screen a member or members slidably in said runways and adapted to spread the walls thereof and relieve their pressure upon the screen when the latter is actuated.

An additional object is to so dispose within a suitable housing a screen-mounting roller as to minimize the size of the housing necessary to accommodate the rolled screen without resulting friction.

These and various other objects the invention attains by the construction hereinafter described and illustrated in the accompanying drawings, wherein:

Fig. 1 is an interior view of a window equipped with the herein disclosed screen.

Fig. 2 is a vertical sectional view of the same taken upon the line 2—2 of Fig. 1.

Fig. 3 is a fragmentary interior eleva-

tional view, showing the relation of a guide member carried by the screen to a runway secured to the window frame when the screen is fully lowered.

Fig. 4 is a fragmentary interior elevational view of a portion of the screen, showing the relation of said guide member and runway when the screen is fully raised.

Fig. 5 is a cross-sectional view through one of the runways and the engaged portion of the screen taken upon the line 5—5 of Fig. 1.

Fig. 6 is a similar cross-sectional view taken upon the line 6—6 of Fig. 1.

Fig. 7 is a fragmentary vertical section taken upon the line 7—7 of Fig. 3, showing a sealing strip carried by the lower end of the screen for engagement with a window sill.

Fig. 8 is an end view of a housing within which the screen is adapted to wind upon a suitable roller.

In these views the reference character 1 designates an ordinary window frame, formed of wood, metal or other suitable material. While Figs. 1 and 2 disclose said frame as provided with a pair of casement windows 2, it is to be understood that the present invention may be applied to any window frame regardless of the specific type of windows. Within the opening formed by the frame 1, a pair of vertically elongated bars 3, hereinafter termed jamb strips, are secured by screws 3^a or other suitable fastening, to the uprights of said frame. Said strips extend substantially the full height of the window opening terminating, however, at their upper ends somewhat below the top of said opening, as best appears in Fig. 1. Upon said strips are mounted the ends of a sheet metal housing 4 which extends substantially fully across the window opening and has rigidly secured to its ends a pair of angular sheet metal brackets 5 which are suitably fastened to the uprights of the frame, as indicated at 5^a. Said brackets are sufficiently flexible to be readily bent to properly center the housing 4 between said uprights, thus compensating for variations in the width of different window openings such as are due to rough carpentry. Longitudinally extending within the housing 4 is a tubular roller

6 formed preferably of sheet metal and disposed for reasons which will presently appear, in a somewhat eccentric relation to said housing. As is common practice one end of said roller carries a pin 7, which is journaled in one end of the housing 4, and a rod 8 which projects from the other extremity of said roller is formed with a terminal tongue 9 which non-rotatively engages in a suitable slot in the opposite end wall. Upon said rod and within said roller, is coiled a spring 10 which is adapted to actuate the roller, in a well-known manner.

To the roller 6 is attached in any suitable manner one extremity of a window screen 11 passing through a slot 12 between the bottom and front walls of the housing 4 and adapted to be downwardly withdrawn from said roller.

20 The free end of the screen is reinforced by a pair of sheet metal strips 13 and 14, clamped against opposite faces of the screen by bolt and nut connections 15 or the like. Between the lower portions of said strips is 25 clamped a strip of rubber or other flexible material 16 projecting some distance below said strips to engage the sill 17 when the screen is fully lowered, thus avoiding any gap between the sill and screen, such as might 30 admit insects. To increase the rigidity of the connection between the strips 13 and 14 and the screen, it is preferred to longitudinally corrugate said strips, as best appears 35 in Fig. 7, the screen being correspondingly corrugated, through its compression between said strips. It is further preferred to form the inner strip 13 with an upper portion which is inwardly bent and outwardly return bent throughout the length of said strip, 40 as indicated at 18, forming a handle for raising and lowering the screen. The part 18 additionally serves as a stop to limit upward travel of the screen by contact with a board 19 which extends across the window opening 45 at the top thereof and conceals the casing. Where it is not necessary to conceal the housing, the stop 18 may engage said housing to limit raising of the screen.

Each lateral margin of the screen 11 is 50 slidable in a runway formed by a pair of sheet metal strips 21 and 22, secured by screws 23 or the like to the inner edge of the corresponding jamb strip 3, and projecting preferably into the window opening somewhat 55 beyond said jamb strip. In order that these runways may snugly engage the screen to establish a seal against the passage of insects to retain the screen selectively adjusted, it is preferred to form one of said strips of a relatively 60 light and resilient metal as brass or bronze, sprung at its free edge toward the companion strip, the latter being preferably of a heavier gauge metal such as sheet steel. In the illustrated embodiment of the invention, the relatively light and resilient strip

21 directly abuts the jamb strip 3, and the relatively heavy and rigid strip 22 is at the inner side of said strip 21.

It is desirable to so engage the margins of the screen in said runways as to tension the screen between said margins and avoid any unsightly sagging of the screen inwardly or outwardly. It is further desirable, to permit the screen to pull free from said runways if it is subjected to some abnormal force which otherwise would perhaps rupture the screen. The present invention subjects the screen to the desired degree of tension by correspondingly beading or corrugating the free edge portions of the strips 21 and 22 and the engaged margins of the screen. The inter-engaging offsets thus formed in the screen and runway members, when properly proportioned, offer a predetermined resistance to horizontal withdrawal of the screen from said runways.

It is highly desirable to prevent any appreciable tilting of the lower or free edge of said screen from its normal horizontal position, since such tilting will tend to unduly increase friction between the screen and its runways, and may produce such a binding of the screen as will make difficult reestablishing of its working position. Also such tilting is likely to disengage one or both of the lower edges of the screen from the runway. As a safe-guard against undue tilting of the screen at its lower edge, the strips 21 and 22 of each runway are formed with complementary corrugations 24 which together produce a substantially tubular enlargement slideably receiving a guide member 25, secured to the binding strips 13 and 14, and having a vertical extent sufficient to resist tilting of the screen. To minimize friction between said guide members and the runways, it is preferred to form the main portions of said members as relatively thin stems, and to provide upon the end portions of said stems heads 25^a acting as slidebearings. The members 25 are mounted upon the screen by a pair of U-shaped brackets 26 which embrace the end portions of the strips 13, 14 and are rigidly secured thereto by bolts and nuts 27 or other suitable fastenings. To prevent interference by the members 25 with final travel of the screen, as it approaches its limiting positions, it is preferred to adapt said members to slide vertically in the brackets 26. Thus the outer ends of said brackets form tubular sockets which slideably receive the stem portions of the members 25. When the screen is drawn down to the sill 17, the guide members 25 are actuated by contact with said sill to the raised positions relative to brackets 26 shown in Fig. 3, and said members assume the lowered positions shown in Fig. 4 when the screen is fully raised.

To positively maintain engagement of the

guide members 25, 25^a in the corrugations 24, it is preferred to form the strip 22 of each runway with a return-bend 28, having an up-set edge 28^a adjacent to the corrugations 24 forming an abutment engageable by the heads 25^a to retain the guide members in place.

Preferably the bottom of the housing 4 is formed at each end of the slot 12 with upturned lugs 29 which restrict the screen from any material lateral travel when being wound upon or withdrawn from its roller. Also it is preferred to form on the brackets 5 a pair of downturned lugs 30 adjacent to the ends 15 of the slot 12 to provide bearing faces against which the edges of the screen may travel in passing through said slot. The lugs 30 exercise the further function of engaging between and spreading apart the top portions 20 of the strips 21 and 22 of each runway so that the latter apply only slight friction to the upper portion of the screen. It is preferred to thus reduce the friction acting upon the upper portion of the screen, because there 25 will ordinarily be no occasion for retaining the screen in any upper position other than fully raised.

It is a decided advantage of the described construction that the corrugations or crimps 30 in the screen margins and runways 21, 22 may be inexpensively formed by feeding them between suitable rolls and that the retention of the screen in the runways by the use of such corrugations has no tendency to 35 damage the screen when through any abnormal shock or jar it is pulled out of the runway.

It is a further advantage of said runways that they subject the screen to sufficient friction to retain the screen selectively adjusted 40 while not unduly resisting sliding of the screen.

The construction is one, furthermore, that permits a quick and convenient mounting of 45 the runways in proper working relation to the screen, since the screen itself may be used to determine the working positions of the runways before the latter are secured in place. Thus in installing the screen, the housing 4 with the screen rolled therein is first 50 properly positioned in the top portion of the window opening as has been described. The resilient runway strips 21 are then placed in their approximate positions of use against 55 the inner edge faces of the jamb boards 3, the screen is downwardly withdrawn a short distance, and the guide members 25, 25^a are pressed into the corrugations of said strips to properly position the upper portions of 60 said strips. Nails 31 are then driven through the upper portion of said strips to maintain said position. The screen is then drawn down a further distance and the strips 21 are nailed in place down to this same point. This 65 process is continued until the strips 21 are

secured in place throughout their entire length. The companion strips 22 are then similarly progressively screwed in place utilizing the guide members 25, 25^a to determine the proper positions of said strip. The screws 23 which position the strips 22, also supplement the nails 31 in positioning the strips 21.

The brackets 26 have a joint thickness considerably exceeding the thickness of the screen 75 and consequently, as the latter is actuated up or down, said brackets serve to spread apart the strips 21 and 22 relieving the screen margins of friction, for some distance above said brackets. Thus said strips gradually close 80 in upon the screen margins some distance above the lower end of the screen so that the wear upon the screen due to friction with the runways is negligible.

The eccentric mounting of the roller 6 in the housing 4 is highly desirable from the viewpoint of minimizing the size of said housing without undue resulting friction between the housing and screen when the latter is fully rolled, or substantially so. I have 85 found that the action of the spring 10 upon the rolled screen and the stress exerted upon the screen through its depending portion, jointly tend to shift it to a position eccentric to the roller 6, as Fig. 2 illustrates. Therefore 90 the location of the axis of said roller at a point forwardly and upwardly removed from the axis of the housing 4 results in establishing a center position of the rolled screen in the casing, and consequently minimizes the required size of said housing. 95

While it will be apparent that the illustrated embodiment of my invention here disclosed is well calculated to adequately fulfill the objects and advantages primarily stated, 100 it is to be understood that the invention is susceptible to variation, modification and change within the spirit and scope of the subjoined claims.

The screws 23 may be tightened or loosened 110 to regulate the friction under which the screen is engaged by the runways.

What I claim is:

1. In a device of the character described, the combination with a sliding window screen, 115 formed with shallow corrugations extending adjacent to its lateral margins, of runways engaging opposite faces of said margins and corrugated correspondingly to said margins.

2. In a device of the character described, 120 the combination with a sliding window screen, formed with corrugations parallel to its lateral margins, of runways engaging said margins, each comprising a pair of members engaging opposite faces of said margins, and corrugated in registration with said marginal corrugations, one of said members being sprung toward the other to impose a frictional restraint on said screen. 125

3. In a device of the character described, 130

the combination with a sliding screen formed with bends adjacent to its margins, of guide members resiliently engaging said margins correspondingly to said margins.

4. A runway for a sliding screen, comprising a pair of adjacent sheet metal strips correspondingly corrugated to embrace a margin of a screen, and reversely corrugated to form a passage for a guide member carried by the screen.

5. In a device of the character described, the combination with a sliding window screen, of a reinforcement extending across an end of said screen, a pair of brackets carried by said screen and projecting beyond the lateral margins of the screen, slide guides carried by said brackets extending beyond said brackets parallel to the lateral margins of the screen and spaced therefrom, said guides having terminal heads at opposite sides of said brackets, and a pair of runways engaged by the lateral margins of the screen and formed with passages receiving the outer end portions of said brackets, the heads of said slide guides being engaged with the walls of said passages.

6. In a device of the character described, the combination with a sliding window screen, of a pair of brackets carried by said screen, at opposite points upon its lateral margins, a pair of slide guides carried by said brackets and elongated beyond said brackets in spaced relation to the lateral margins of the screen, and slideable in said brackets parallel to said margins, means carried by said slide guides limiting their sliding travel relative to said brackets, a pair of runways engaged by the lateral margins of the screen, and formed with passages slideably receiving said slide guides, and an abutment limiting travel of the screen in one direction, encountered by said slide guides as the screen approaches said abutment, whereby the slide guides are shifted reversely to actuation of the screen.

7. In a device of the character described, the combination with a sliding window screen and a pair of slide guides for said screen elongated in parallelism with the lateral margins of the screen, of supports for said slide guides carried by said screen adjacent to said lateral margins, affording said guides a limited travel relative to the screen parallel to said margins, a pair of runways engaging the lateral margins of the screen and formed with passages receiving said slide guides, and means engageable by said slide guides for limiting travel of the screen in both directions of its sliding, said guides being moveable in said supports by said limiting means, to increase the range of permissible travel of the screen.

8. In a device of the character described, the combination with a sliding screen, of a sealing member carried by an end of said

screen, a pair of slide guides elongated in the direction of sliding of said screen, a pair of brackets mounting said slide guides, carried by said screen, adjacent to said sealing member, and respectively adjacent to lateral margins of the screen, a pair of runways engaging the corresponding margins of said screen and forming passages receiving said slide guides, and an abutment engageable by said sealing member in the extended position of the screen, said slide guides being slideable in said brackets through engagement of said guides with said abutment, whereby the sealing member may closely approach said abutment.

9. In a device of the character described, the combination with a sliding window screen, of a bracket projecting laterally beyond an edge of said screen, forming a slide bearing, a slide guide slideable in said bearing in the direction of sliding of the screen, and terminally formed with heads of a diameter exceeding that of said bearing, said heads limiting sliding of said guide in said bearing, and a runway engaging said screen margin formed with a passage receiving said slide guide.

10. In a device of the character described, the combination with a sliding screen, of a bracket projecting laterally beyond an edge of said screen, a guide carried by said bracket elongated in the direction of sliding of the screen and formed terminally with guide heads, and a runway comprising sheet metal walls extending at opposite sides of the screen margin carrying said bracket, and forming a passage receiving said guide, one of said walls being return bent between said walls and forming an abutment engageable with the heads of said guide to retain the guide in said passage.

In testimony whereof I sign this specification.

HARRY M. COATES.
